(57) **CLAIM**

The ornamental design for a weather station as shown and described.

DESCRIPTION

FIG. 1 is a first perspective view of a weather station of the present invention.

FIG. 2 is a second perspective view of the weather station of FIG. 1.

FIG. 3 is a front view of the weather station of FIG. 1.

FIG. 4 is a rear view of the weather station of FIG. 1.

FIG. 5 is a right side view of the weather station of FIG. 1.

FIG. 6 is a left side view of the weather station of FIG. 1.

FIG. 7 is a top view of the weather station of FIG. 1; and,

FIG. 8 is a bottom view of the weather station of FIG. 1.

The evenly spaced broken lines in the drawings show portions of the weather station, which form no part of the claimed design.
